(57) CLAIM

We claim the ornamental design for a helmet for hockey goalie or the like, as shown and described.

DESCRIPTION

FIG. 1 is a perspective view of a helmet for hockey goalie or the like showing our new design;

FIG. 2 is a right side elevation view thereof, the opposite side being a mirror image;

FIG. 3 is a front elevation view thereof;

FIG. 4 is a top plan view thereof;

FIG. 5 is a rear elevation view thereof; and,

FIG. 6 is a bottom plan view thereof.

The details shown in broken lines form no part of the claimed design.
